[57] CLAIM

The ornamental design for a tie clip, as shown and described.

DESCRIPTION

FIG. 1 is a perspective view of a tie clip showing my new design;

FIG. 2 is a bottom rear perspective view;

FIG. 3 is a top plan view;

FIG. 4 is a front elevational view;

FIG. 5 is a bottom plan view;

FIG. 6 is a rear elevational view;

FIG. 7 is a right side elevational view;

FIG. 8 is a left side elevational view;

FIG. 9 is a fragmented perspective view of the inner surface of the clip, the remainder being omitted for ease of illustration;

FIG. 10 is a top front perspective of a tie clip showing a second embodiment of my new design;

FIG. 11 is a bottom rear perspective view of FIG. 10;

FIG. 12 is a top plan view of FIG. 10;

FIG. 13 is a front elevational view of FIG. 10;

FIG. 14 is a bottom plan view of FIG. 10;

FIG. 15 is a rear elevational view of FIG. 10;

FIG. 16 is a right side elevational view of FIG. 10;

FIG. 17 is a left side elevational view of FIG. 10; and,

FIG. 18 is a fragmented perspective view of inner surface of the clip, the remainder being omitted for ease of illustration.
